D11-98. OR D16,863 EX

D11-107. XR D16,863 EX

DESIGN.

—
J. B. HOWELL.

BADGE.

No. 16,863.

Patented Aug. 24, 1886.

Witnesses:
David S. Williams
William D. Conner

Inventor:
Joseph B. Howell
by his Attorneys
Howell and Son

UNITED STATES PATENT OFFICE.

JOSEPH B. HOWELL, OF PHILADELPHIA, PENNSYLVANIA, ASSIGNOR TO HARRY C. STOUT, TRUSTEE, OF SAME PLACE.

DESIGN FOR A BADGE.

SPECIFICATION forming part of Design No. 16,863, dated August 24, 1886.

Application filed June 23, 1886. Serial No. 206,053. Term of patent 7 years.

To all whom it may concern:

Be it known that I, JOSEPH B. HOWELL, a citizen of the United States, residing in Philadelphia, Pennsylvania, have invented a new and original Design for a Badge, of which the following is a specification.

My design for a badge is fully illustrated in the drawing, and comprises the head-piece A, ribbon B, and medal D, the ornamentation of the head-piece and medal constituting the main features of the design. The head-piece has a cross-bar, α , with flame-like radiations α' at the top, the main body of the head-piece being of general rectangular outline, and having at the bottom a central recess and a projection midway of the same. On the face of the head-piece is the representation of an eagle grasping crossed swords.

The medal comprises a center piece containing the representation of a winged female figure about to place a crown upon the head of a kneeling armed knight, and around this representation is a wreathed border. Beneath this representation is a space inclosed by a smaller wreath.

I claim—

1. In a design for a badge, the head-piece comprising a plate of general rectangular shape, having projection and recess at the lower side, provided with radiations at the top, and containing the representation of an eagle grasping crossed swords, all substantially as described and shown.

2. In a design for a badge, the medal comprising the central representation of a winged female figure applying a crown to the head of a kneeling knight, and a wreathed border for the said representation, all substantially as described and shown.

3. The herein-described design for a badge, said design consisting of the head-piece containing the representation of an eagle grasping crossed swords, the ribbon piece, and the medal containing the representation of a female figure applying a crown to the head of a kneeling knight, all substantially as described and shown.

In testimony whereof I have signed my name to this specification in the presence of two subscribing witnesses.

JOSEPH B. HOWELL.

Witnesses:

HARRY SMITH,
HUBERT HOWSON.